UNITED STATES PATENT OFFICE.

ADOLPH W. MACHLET, OF ELIZABETH, NEW JERSEY.

APPARATUS FOR CASE-HARDENING, &c.

1,337,244.

Specification of Letters Patent. Patented Apr. 20, 1920.

Application filed June 29, 1918. Serial No. 242,622.

To all whom it may concern:

Be it known that I, ADOLPH W. MACHLET, a citizen of the United States, residing in Elizabeth, in the county of Union and State 5 of New Jersey, have invented certain new and useful Improvements in Apparatus for Case-Hardening, &c., of which the following is a specification.

Certain features of this invention relate 10 to case-hardening machines of the type disclosed in the patents granted to me No. 822,460, dated June 5, 1906, No. 847,588, dated March 19, 1907, No. 884,180, dated April 7, 1908, No. 884,181, dated April 7, 15 1908, and No. 961,305, dated June 14, 1910, in which steel or other articles to be case-hardened are placed in a retort, through 20 which a current of carburizing gas flows while the retort is maintained at a carburizing heat and kept in motion to agitate the articles. Several features of the invention 25 may be used for other purposes than case-hardening, especially where it is desired to bring metal articles to a high heat, with provision for rapidly discharging and 30 recharging the heated retort. One feature of the invention relates to the construction of a closed retort, whether used for the above-mentioned or other purposes.

In the apparatus disclosed in said patents, after the case-hardening of the articles was completed, the cover or lid at one end of the retort was removed, and the articles were raked or pulled out, and a fresh batch of 35 articles pushed into the retort. These operations consumed considerable time, keeping down the earning power of the apparatus. Moreover, considerable waste of heat from the furnace was entailed, owing to the duration 40 of the discharging and recharging operations.

According to certain of the present improvements, the operations of discharging and recharging are very quickly and readily 45 performed, thus increasing the efficiency of the apparatus and substantially reducing the loss of heat from the furnace.

To effect a ready discharge, the retort is carried in a manner to be capable of dipping or swinging downwardly at its discharge end. The interval between removing the cover (for discharging and recharging the retort) and replacing the same, is so 50 shortened, that the flames within the furnace 55 may in some cases advantageously be kept

going full blast during the discharging and recharging operations, and the retort may also be kept in rotation; the supply of carburizing gas being of course shut off before the removal of the cover, to be turned on 60 again as soon as the cover is replaced upon the retort.

The same device which depresses one end of the furnace to discharge the retort, may be reversed to bring the furnace not only 65 back up to horizontal working position, but also to elevate farther the discharge end of the retort, and depress its other end, thus facilitating and expediting the recharging of the retort, which hence can be very 70 quickly accomplished.

Suitable flexible connections are provided between the furnace and the supply for mixed air and fuel going to the flame-chamber, these connections permitting the up-and-down swinging of the furnace; and another flexible connection may be provided for supplying the carburizing gas to the end of the retort opposite its discharge end.

Taking up now the improvements in re- 80 tort construction, it has been found in practice that a revolving retort in which articles are case-hardened or treated, is subject in the course of time to distortion and other deleterious changes, due to the alternate 85 heating and cooling thereof, especially for carburizing purposes; the carburizing or other gas being apt to combine with the iron of which the retort is made. It has been found that the retort, if made of cast iron, 90 gradually and permanently expands in diameter. Moreover, the cast iron retort gradually increases in length, and is apt to become distorted in the course of time, some parts thereof slowly increasing in dimensions 95 out of proportion to other parts. If the retort is made of steel, it may gradually shrink in diameter; and owing to the formation of scale, the body of the retort is apt to grow thinner after long use.

Accordingly, among the objects of my invention are these, to effect a reduction in the escape of heat from the ends of the furnace, especially the end thereof which is opposite from the discharge end of the 105 retort; to avoid deleterious changes in the retort, and particularly to avoid distortion or substantial permanent changes in the dimensions thereof; and to increase the life of the retort, and consequently reduce or 110

avoid the necessity of replacing the same; and I further aim to increase the load-carrying capacity of the retort when heated, to avoid the necessity of fitting it up with a partition at the end opposite from its discharge end, to reduce the cost of maintenance, to reduce the consumption of heating gas and carburizing gas; and generally to lower the cost of carburizing or heat-treating metal articles.

One of the means for substantially reducing the loss of heat from the furnace, is to reduce the diameter of that portion of the retort which projects through one of the ends of the furnace to rest upon the exterior support. This reduction permits said end of the furnace to be much more nearly closed by the use of fire-brick or other refractory material than has been found possible heretofore, whereby escape of heat is substantially reduced, and consequent saving in fuel effected. This portion of the retort has an end within the flame-chamber of the furnace, said end provided with a central projecting tubular or hub-like portion, which extends out through a small opening provided in the end of the furnace; said projecting hub carrying a wheel which may support the retort upon the usual exterior rolls mounted upon the ends of the furnace; a sprocket or other gear-wheel being also connected to this projecting hub for revolving the retort; and a supply of carbonizing or other gas being introduced through this tubular hub into the interior of the retort.

In order to permit the construction of the retort in the just-described form, and avoid liability of collapse of a long-used retort at the high heat which is necessary in carbonizing, I employ an alloy of nickel, chrome and iron, or nichrome, this alloy being usually about 60% of nickel, 20 or 30% of chrome, and 10 or 20% of iron. The retort, with its end and projecting hub, is cast in a single piece of nichrome, and, notwithstanding the small diameter of said projecting hub, (which of course at its inner portion becomes highly heated) is well able to support the load of the retort and of a heavy charge of articles therein. Moreover, this retort is heat-resisting, and is well adapted to withstand much higher heats than would be the case with steel tubing, or with cast-steel or cast-iron; whereby a substantial advantage is gained in the carbonizing operation. The new retort, moreover, does not permanently expand, and hence does not out-grow its clearances, as is apt to be the case with a retort which is made from a steel tubing; and hence the original fitting of the retort to the furnace may be made much closer, since no room needs to be allowed for the permanent expansion of the retort. It results that a great and continuous loss of heat through the clearances or crevices

around the ends of the retort is saved; this being in addition to the substantial closing up by fire-brick of one end of the furnace, which has heretofore not been found possible. Moreover, the retort is highly durable and practically indestructible. It is obvious that this retort may be made in other forms, while retaining many or all of the advantages above set forth, and also that it may be used in other than tilting furnaces.

Another feature of the present invention resides in means for controlling the heat of different portions of the retort. One advantage gained is that more heat may be supplied to the ends of the retort than to the middle portion thereof, thereby to compensate for the tendency of heat to escape from the ends of the retort more rapidly than from the middle thereof; and hence the retort may be maintained at substantially uniform heat throughout its length. Or, when desired, the middle may be heated more than the end portions. Where a single large article is to be case-hardened or heat-treated only at one portion thereof, the same may be inserted in the retort, and the desired portion thereof may be heated, other portions of the retort, and hence of the work, not being heated. In this way, for example, one portion of a large shaft may be case-hardened or treated, while another portion or portions may not be. Or several long shafts may be inserted together into the retort, and their ends only may be case-hardened, by using only the end manifolds. Another advantage gained is that the capacity of the retort may be varied. When desired, the inner head which is attached to the cover and forms one end of the retort proper, may be adjusted along the retort so as to shorten the chamber which contains the articles to be carburized; and only such shortened portion needs to be heated, this being permitted by the use of the aforementioned device for regulating the heat of the various portions of the retort. By means of this improvement, several variations may be made in the capacity of the retort.

To carry out the heat-regulating feature of the invention, suitable manifolds are placed along the furnace, and each is provided with an independent supply of mixed air and fuel, so that each manifold may be cut out of use, whereby as much of the length of the retort may be heated as desired, without the necessity of consuming gas for heating the portion of the retort which it is not desired to heat.

Other features and advantages will hereinafter appear.

In the accompanying drawings,

Figure 1 is a perspective elevation of a carburizing machine embodying the present improvements in one form.

Fig. 1^a shows an assortment of stems for

connecting the retort cover to the head which is settable to vary the effective length of the retort.

Fig. 2 is a perspective illustrating the machine from its opposite end.

Fig. 3 is a part-sectional side elevation of the machine, showing the retort, however, in the form of a steel tube projecting from both ends of the furnace, since certain of my improvements can be used with various kinds of retorts.

Fig. 4 is an end elevation of the machine showing the discharge end thereof.

Fig. 5 is a detail plan of certain retort driving connections.

Fig. 6 is an elevation of the machine taken at the end opposite from Fig. 4.

Fig. 7 is a part-sectional view illustrating the preferred form of retort and furnace-end.

Fig. 8 is an enlarged detail of a hook for securing the cover upon the retort.

The furnace is illustrated in the form of a cylindrical horizontal barrel 10 suspended between its heads or ends 12, 13 by means of gudgeons or trunnions 14 projecting from flanges or brackets 15 on opposite sides of the furnace and mounted in bearings 16 on the tops of standards 17 which may be connected at their lower portions by a cross-tie 18. This furnace has a complete interior cylindrical lining 19 of fire brick or other refractory material, as well as similar disks or annular linings 20, 21 for its rear and front heads 13 and 12; said heads having central openings 22, 23 through which extend, at Fig. 3, projecting ends 24, 25 of a cylindrical or tubular retort 26.

The retort is revolvably supported by means of its projecting ends exteriorly of the furnace upon pairs of rolls 27, 28; the retort having at one end flanges 29 forming a groove in which the rolls run to prevent endwise displacement of the retort, thus preventing it from falling when tilted up or down.

An annular space is left between the retort and the cylindrical lining of the furnace to form a flame chamber 30; and the retort is provided with spacing disks forming ends or heads 31, 32 which are confined within the ends of said flame chamber 30, and comprise disks 33 of asbestos or other refractory material, each confined between metal disks. The burners 34 within the flame chamber are seen at the top of the furnace at Fig. 3.

For keeping the retort in rotation during the cementation of the articles, as well as during the tilting of the furnace, power may be derived from a motor or other source through a chain belt 35 running over a sprocket wheel 36 which drives a concentric bevel pinion 37 at low speed. If said belt is driven at high speed, a speed-reducing

mechanism may be provided in a casing 38; and a suitable clutch 38^a for starting and stopping the rotation of the retort may be mounted upon the shaft 39 of the pinion 37 and controlled through a handle 40. Said bevel pinion 37 meshes with another bevel pinion 41 provided upon one end of a shaft 42 which extends longitudinally of the furnace, and carries at its other end a sprocket wheel 43 connected by a chain 44 to a larger sprocket wheel 45, which is fixed upon one end of the retort, whereby the latter is revolved slowly. Said longitudinal shaft 42 is supported at one end in a bearing 46 in projections provided upon the furnace head 13, the other end of shaft 42 having a bearing in a box or bracket 47 connected to a furnace trunnion; and hence all these gears may swing with the furnace as the latter turns upon its trunnions. The axis of the sprocket wheel 36, which is connected to the source of power, is concentric with the axis of the furnace trunnions or gudgeons, and thus the tilting of the furnace does not disconnect the bevel pinions 37, 41, and so the retort may remain in rotation during the tilting of the furnace, which is a convenience in discharging the retort, and favors a reduction of the time elapsing between the completion of the cementation of one batch and the beginning of the cementation of the next batch, since no time need be consumed in starting and stopping the retort. The speed-reducing device 38 is placed at a comparatively cool part of the furnace, all the remaining portion of the retort-rotating train operating slowly, and not liable to faulty operation by reason of the high heat.

Carburizing gas is supplied to the retort through a pipe 48 which may be of flexible metallic construction, to accommodate the tilting of the furnace, said flexible pipe 48 connected with the upper end of a vertical pipe 49 whose lower end is connected by a gland 50 to an inlet pipe 51 which extends through the end of the retort and also through its inner partition or head 31, Fig. 3, to supply the retort with gas. The upper end of said pipe 49 may be loosely confined between supports 52 projecting horizontally from the head 13 of the furnace, and united at their outer ends by cross-pins 53, Fig. 2, which confine the pipe 49, so that said pipe is prevented from substantial displacement in any direction, but still is allowed a certain amount of play at its upper end, to accommodate displacements due to heating and cooling of the retort, or to other reasons.

At its opposite end, the retort has an exterior cover or lid 54, which is provided with pivoted sliding hooks 55 catching over a flange 56 which surrounds and is rigid with the projecting end portion of the retort; said hooks being drawn tight, thus securing the

- cover, by means of wing nuts 57. Each hook has at one end a tooth to hook over the flange 56, and at the other a stem 58, upon which the nut 57 is threaded. The hook 5 has between its ends a longitudinal slot 59, whereby it is pivotally carried upon a pin 60, which crosses the housing 61 in which the hook slides and turns, and upon which the wing nut 57 bears.
- 10 This cover 54 is joined by a pipe 62 to the interior head 32 of the retort, so that the interior head 32 will be pulled off with said cover. Said pipe 62 also serves as a vent, to permit the vitiated carburizing gas to escape 15 from the retort; said gas being usually supplied to the retort under low pressure. The end of the pipe 62 projects from the cover 54 (see Fig. 1), and may serve as a convenience upon which to attach a long bar or 20 handle for use in removing the cover; or where the cover is of large size and heavy, the same may be manipulated by means of a fall and tackle, if desired. A regulating valve 63, Fig. 3, may be provided upon vent 25 pipe 62, if desired.
- Air and gas are separately supplied to the apparatus through pipes which are flexible to accommodate the swinging movements of the furnace; and the air and gas are mixed 30 and distributed to the burners within the flame chamber in a manner that will hereinafter be described.
- In operating the apparatus, the cover 54 at the discharge end of the retort 26 is removed; and the articles to be case-hardened 35 are placed in the retort. Thereupon, the cover 54 is restored to position, the inner partition or head 32, which is connected to said cover, taking the position seen at Fig. 3.
- 40 Then the hooks 55 are caught over the flange 56 and the wing nuts 57 tightened. Gas and air may be admitted to the furnace and ignited at a small outlet 64 provided in a plug 65 which closes a hole in the end 12 45 of the furnace just above the discharge end of the retort; said opening also serving as a peep hole for inspection of the interior of the furnace. Then, by manipulating the handle 40, the clutch is thrown into use 50 which starts the operation of the gears and chain which rotate the retort. The retort is brought up to carburizing heat, and the heat is maintained until the articles are cemented. Thereupon, the supply of carburizing gas is cut off from the retort by 55 closing a valve 66, Fig. 2, and the wing nuts 57 are turned to release the hooks 55, which are withdrawn from the flange 56. Then the cover 54 is pulled off, together with the 60 inner head 32, which is thus removed from the retort. Then a hand-wheel 67 is employed to rotate a shaft 68 mounted in bearings 69 upon the main frame of the machine, and having a worm 70 which engages 65 a worm-wheel or segment 71 mounted upon

the furnace barrel, thereby tilting said barrel upon its trunnions from normal level position to depress the open end of the retort and discharge the articles therefrom to a suitable receptacle. The retort is self-discharging when depressed. Thereupon by using the hand-wheel 67 the worm shaft is rotated backwardly to tilt up the furnace; this operation continuing until the open end of the retort is elevated in the opposite direction, *i. e.*, above horizontal position, to facilitate recharging at the same end. After a fresh batch of articles is inserted, the cover 54 with its head 32 may be restored, and the hand-wheel 67 may then be employed to 70 restore the furnace to horizontal position. During these operations, the flames continue to play around the retort, so that it is kept at carburizing heat, whereby the freshly inserted articles are quickly brought up to 75 carburizing heat; the supply of carburizing gas being again turned on. The horizontal position of the retort may be conveniently ascertained by means of a gage or index 71^a mounted on the framework to coincide with 80 a plate 71^b on the furnace.

At Fig. 7 the retort is seen in the form of a casting 72 of nichrome, the casting including an end 73 within the flame chamber of the furnace, thereby permitting this end 95 of the furnace to be substantially closed by a fire-brick structure or disk 74 of refractory material; a small central opening 75 being left in said disk for the projection therethrough of a hub 76 cast upon the retort; said opening 75 being so small that the loss of heat therethrough is much reduced as compared with former constructions; and the end 73 of the retort also serving as a baffle to interfere with the direct 100 radiation of heat from the body of the flame chamber through said opening. There may be secured upon the outer end of the hub 76 a wheel 77, having flanges 78 with an intervening cylindrical periphery to rest upon 105 the rolls 27 seen at Fig. 6, whereby the retort is revolvably supported and also prevented from falling at the tilting operation, or from otherwise moving endwise. This wheel 77 may be held on the hub 76 by a key 110 79, and may also have thereon the sprocket 45 over which runs the driving chain 44 that revolves the retort.

The hub 76 may be hollow or provided with a longitudinal central opening 80, making a tubular hub for the introduction of carburizing gas into the retort; said carburizing gas being supplied through stationary pipe 49 and gland 50, the latter permitting the retort to rotate while connected 115 with said stationary pipe 49. Said gland may be attached by a flange to the hub of wheel 77, which is attached to hub 76. It will be seen that the hollow hub 76 is of relatively small diameter, and that it is also 120 130

subjected to high carburizing heat, which would be sufficient to weaken and collapse a charged retort if made of iron or steel in this form; but the nichrome construction of 5 the retort enables this form to be used without liability of collapse, as well as attaining other advantages, including those hereinbefore described. The movable head may be in the form of a single solid disk 80^a of 10 nichrome, and longitudinal ribs 80^b may be cast within the barrel, to aid in agitating the articles, and permit the barrel to be heavily charged without incurring liability 15 of the articles slipping around the interior periphery of the barrel.

The distribution of the mixed fuel and gas may be effected by the following means; although it will be understood that this portion of my improvements may be used with 20 other furnaces, whether tilting or not; and it will be further understood that the tilting of the furnace may be used to advantage in connection with other means of supplying fuel thereto.

25 There are illustrated two short end manifolds 81, each comprising two burners 34, and one long middle manifold 82, comprising four burners. These manifolds and burners are duplicated on the opposite sides 30 of the furnace. The opposite short manifolds 81 at each end of the furnace are connected by an individual pipe 83, which may be of U-form; and the large middle manifolds 82 are connected by another pipe 84. 35 A mixture of air and gas is conducted to each of the pipes 83, 84 through an individual connection 85, which receives compressed air from an individual supply pipe 86 and gas from a supply pipe 87, the point 40 of mixture of the gas and air being at the junction of pipe 87 with connection 85, and the control of each being determined by valves 88 and 89 in pipes 86 and 87. Each 45 of the three cross-pipes 83 is independently supplied with gas and air in the same manner; a main air supply pipe 90 being branched to supply the three pipes 86, and the main gas supply pipe 91 being likewise divided into branches; and each branch may

50 have its independent valve 88 or 89, so that air and gas of the desired mixture may be supplied to each cross-pipe 83, 84 independently of the other cross-pipes, whereby any manifold may be either working or silenced, 55 as desired. The pipes 90 and 91 may be of flexible metallic construction, to accommodate the tilting of the furnace.

At Fig. 1^a, is illustrated a set of pipes 62, 62^a and 62^b of assorted lengths, one (62) 60 being the length seen in the other views, and another (62^a) being of a length to bring the head 32 to a position to shorten the retort chamber to an extent suitable when the front manifolds 81 are cut out; the third 65 pipe (62^b) being longer, to be used when

both the front small manifolds 81 and the long manifolds 82 are cut out.

As seen at Figs. 3 and 7, the furnace may have one or more clean-out holes 92 in its bottom portion, each hole normally closed 70 by means of an underlying brick 93, which is supported by a metal plate 94, the latter being set up on studs 95 pendent from the bottom of the furnace and threaded at their lower ends to receive supporting wing-nuts 75 96. By turning down the nuts, the plate may be removed, together with the closing brick, giving access to the interior of the furnace.

Variations may be resorted to within the 80 scope of my invention, and portions of the improvements may be used without others.

Having thus described my invention, I claim:

1. The combination of a closed retort, a 85 furnace having a flame chamber within which the retort is supported, said retort having at one end a movable closure, and means for supporting the furnace for movement to depress the retort for discharging 90 the same, said retort being self-discharging by reason of such depression thereof.

2. The combination with a closed revoluble retort, having an opening in one end through which the retort is both charged 95 and discharged, and a closure for said opening, of a furnace having a flame chamber within which said retort is supported, said furnace mounted for a tilting movement to discharge the retort, which is self-discharging- 100

3. The combination with a revoluble closed retort, having an opening in one end through which the retort is both charged and discharged, and a closure for said opening, of 105 a tiltable furnace having a flame chamber within which said retort is supported, said furnace mounted for both a depressing movement below horizontal position to discharge the retort, and an elevating movement above horizontal position for charging the retort, and means for rotating said retort during the depressing and elevating movements.

4. The combination with a revoluble retort, of a tiltable furnace having a flame chamber within which said retort is supported, said furnace mounted for a depressing movement below normal to incline the retort in one direction to discharge the retort at one end thereof, and for an elevating movement above normal to incline the retort in the opposite direction to facilitate charging the retort at the same end, and means for rotating said retort within said 115 furnace while the same is stationary and also during the tilting of the retort in both directions.

5. The combination with a revoluble retort, of a furnace having a flame chamber 120 125 130

- within which said retort is supported, said furnace mounted for a tilting movement in opposite directions to charge and discharge the retort at the same end thereof, means 5 for rotating said retort, said rotating means including a gear on the end of the retort opposite from its charging and discharging end, and a train of driving connections extending from said gear to about the axis of 10 the tilting movement of the furnace.
6. The combination with a revoluble retort, of a furnace having a flame chamber within which said retort is supported, said furnace mounted for a tilting movement to 15 discharge the retort, means for rotating said retort, said rotating means including a gear on an end of the retort, a train of driving connections extending from said gear to about the axis of the tilting movement of 20 the furnace, said train including a sprocket chain running over said gear, a sprocket wheel over which said chain runs, a shaft extending toward the axis of tilting movement of the furnace, and driving gearing at 25 about said center of the tilting movement.
7. The combination with a revoluble retort, of a furnace having a flame chamber within which said retort is supported, said furnace mounted for a tilting movement to 30 discharge the retort, means for rotating said retort, said rotating means including a gear on an end of the retort, a train of driving connections extending from said gear to about the axis of the tilting movement of 35 the furnace, said train including a sprocket chain running over said gear, a sprocket wheel over which said chain runs, a shaft extending toward the axis of tilting movement of the furnace, and also including a 40 bevel pinion upon said shaft, a second bevel pinion having an axis of rotation about concentric with the axis of tilting of said furnace, and a driving pulley for the last-mentioned bevel pinion.
- 45 8. The combination with a revoluble retort, of a furnace having a flame chamber within which said retort is supported, said furnace mounted for a tilting movement to discharge the retort, means for rotating said 50 retort, said rotating means including a gear on an end of the retort, a train of driving connections extending from said gear to about the axis of the tilting movement of the furnace, said train including a sprocket 55 chain running over said gear, a sprocket wheel over which said chain runs, a shaft extending toward the axis of tilting movement of the furnace, and also including a bevel pinion upon said shaft, a second bevel 60 pinion having an axis of rotation about concentric with the axis of tilting of said furnace, and a driving pulley for the last-mentioned bevel pinion, a speed-reducing device being included between said driving pulley 65 and the last-mentioned bevel pinion.

9. The combination with a retort, of a furnace having a flame chamber within which said retort is mounted, said furnace mounted for tilting movement to depress said retort for discharging the same, burners being 70 provided in said furnace, and connections from said burners to a source of supply, said connections including members which are flexible to accommodate the tilting of the furnace, said members arranged above the 75 furnace.

10. The combination of a furnace mounted to tilt and having a flame chamber, a retort suspended within said flame chamber, and means for supplying metal-treating gas 80 into one end of said retort, said supplying means including a member which is flexible to accommodate the tilting movement of the furnace and retort, said retort having a vent at a point remote from said supply. 85

11. The combination of a furnace having a flame chamber, a retort suspended within said flame chamber, and means for supplying metal-treating gas to one end of said retort, said supplying means including a 90 flexible member, said retort having a cover at the end opposite from said supply, and said furnace mounted to depress the end of said retort having said cover below normal horizontal position while elevating the opposite end, to discharge the retort when the cover is removed, and to elevate said discharge end while depressing the other end below horizontal, to facilitate recharging. 95

12. The combination of a furnace in cum- 100 bent position and having a flame chamber, a closed retort extending through the flame chamber and projecting at its ends from the furnace, supporting means for said retort upon the exterior of the furnace, means connected to said retort at one of its projecting ends for revolving the same in all positions to which the furnace is tilted, means for supporting the furnace between its ends for a tilting movement, and means for supplying 105 gas to said retort in all positions thereof. 110

13. The combination of a furnace in cum- 115 bent position and having a flame chamber, a retort extending through the flame chamber and projecting at its ends from the furnace, supporting means for said retort upon the exterior of the furnace, means connected to said retort at one of its projecting ends for revolving the same in all positions to which the furnace is tilted, means for supporting 120 the furnace between its ends for a tilting movement, flexible connections for fuel extending to said furnace, and a flexible connection for metal-treating gas extending to said retort. 125

14. The combination of a furnace having a cylindrical flame chamber, a standard or support, trunnions whereby said furnace is mounted between its ends upon said support for tilting either up or down from horizon- 130

- tal position, a cylindrical retort extending through said flame chamber and projecting at its ends from said furnace, supporting means for said retort exterior to said furnace, means connected to a projecting part of said retort for revolving the same, said revolving means extending to a point about concentric with said trunnions and capable of rotating the retort in all positions of the furnace, a flexible connection to one end of said retort for supplying metal-treating gas thereto, a closure at the other end of said retort for permitting the same to be discharged and recharged, and means connected to said furnace for supplying fuel thereto. 5
10. The combination of a furnace having a flame chamber, a retort supported within said flame chamber, groups of burners in said furnace, means for supplying a mixture of air and fuel to each group, and means for closing the supply to each group independently of the remaining group or groups. 15
11. The combination of a furnace having a flame chamber, a retort supported in said flame chamber, groups of burners on opposite sides of the furnace, the groups on one side being paired with the groups on the opposite side, means for supplying mixed air and fuel to each pair of groups independently of the other pair or pairs, and means for cutting out any pair or pairs of the groups. 20
12. The combination of a furnace having a flame chamber, a retort supported in said flame chamber, groups of burners on opposite sides of the furnace, the groups on one side being separate from one another and paired with the groups on the opposite side, means for supplying mixed air and fuel to each pair of groups independently of the other pair or pairs, and means for cutting out any pair or pairs of the groups. 25
13. The combination of a furnace having a flame chamber, a retort supported in said flame chamber, groups of burners on opposite sides of the furnace, the groups on one side being separate from one another and paired with the groups on the opposite side, means for supplying mixed air and fuel to each pair of groups independently of the other pair or pairs, and means for cutting out any pair or pairs of the groups. 30
14. The combination of a furnace having a flame chamber, a retort supported in said flame chamber, groups of burners on opposite sides of the furnace, the groups on one side being separate from one another and paired with the groups on the opposite side, means for supplying mixed air and fuel to each pair of groups independently of the other pair or pairs, and means for cutting out any pair or pairs of the groups. 35
15. The combination of a furnace having a flame chamber, a retort supported in said flame chamber, groups of burners on opposite sides of the furnace, the groups on one side being separate from one another and paired with the groups on the opposite side, means for supplying mixed air and fuel to each pair of groups independently of the other pair or pairs, and means for cutting out any pair or pairs of the groups. 40
16. The combination of a furnace having a flame chamber, a retort supported in said flame chamber, groups of burners on opposite sides of the furnace, the groups on one side being separate from one another and paired with the groups on the opposite side, means for supplying mixed air and fuel to each pair of groups independently of the other pair or pairs, and means for cutting out any pair or pairs of the groups. 45
17. The combination of a furnace having a flame chamber, a retort supported in said flame chamber, groups of burners on opposite sides of the furnace, the groups on one side being separate from one another and paired with the groups on the opposite side, means for supplying mixed air and fuel to each pair of groups independently of the other pair or pairs, and means for cutting out any pair or pairs of the groups. 50
18. The combination with a furnace having a flame chamber and a retort mounted therein, of groups of burners upon opposite sides of the furnace to discharge within said flame chamber, the groups upon one side being separate from one another and paired with those upon the other side, means affording an open communication between the groups of each pair independently of the other pairs, means for supplying mixed air and gas to said communicating means and means for cutting off the supply from any pair or pairs of the groups. 55
19. The combination of a furnace having a flame chamber, a retort mounted within said flame chamber, groups of burners upon opposite sides of the furnace, the groups upon one side being separate from one another and paired with those upon the other side, independent cross-connections for the paired groups, a supply for gas, a supply for air, branches from each of said supplies to said independent cross-connections, and means for controlling the flow of each of said branches independently of the others. 60
20. The combination of a furnace having a flame chamber, a retort mounted within said flame chamber, groups of burners upon opposite sides of the furnace, the groups upon one side being separate from one another and paired with those upon the opposite side, independent cross-connections for the paired groups, a supply for gas, a supply for air, branches from each of said supplies to said independent cross-connections, and means for controlling the flow of each of said branches independently of the others. 65
21. The combination of a furnace having a flame chamber therein, a retort within said flame chamber, independent manifolds upon each side of the furnace, each manifold comprising a group of burners, the manifolds upon one side being paired with those upon the other side, a supply for gas, a supply for air, means for mixing and distributing the air and gas to each pair of manifolds, and means for independently controlling each pair of manifolds independently of the others. 70
22. The combination with a furnace having a flame chamber therein, of a retort within said flame chamber, and selective means for heating either a portion or all of said retort at will, means being provided for substantially shortening the work chamber within the retort. 75
23. The combination with a closed retort, of means for revolving, heating and tilting down one end of the retort to discharge the same, and tilting up the same end of the retort for re-charging the same, said end having a removable closure. 80
24. The combination with a furnace having a flame chamber, of a carburizing retort in said flame chamber, comprising a casting of the herein-described nichrome, said retort extending through the ends of the furnace, and means upon the exterior of the furnace for supporting the retort for revolution, said furnace ends having openings fitted to said retort without allowance for permanent expansion of the latter. 85
25. The combination with a furnace having a flame chamber, of a retort in said flame chamber, comprising a casting of the herein-described nichrome, said retort extending through the ends of the furnace. 90

- means upon the exterior of the furnace for supporting the retort for revolution, said furnace substantially closed at one end and having an opening smaller than the body 5 of the retort, and the retort closed within the flame chamber and having a hollow hub portion of reduced diameter extending through the end of the furnace and supported for revolution upon the exterior of 10 the furnace, and a supply for gas to pass through said hollow hub.
26. The combination with a furnace having a flame chamber, of a retort in said flame chamber, comprising a casting of the 15 herein-described nichrome, said retort extending through the ends of the furnace, means upon the exterior of the furnace for supporting the retort for revolution, said furnace substantially closed at one end and 20 having an opening smaller than the body of the retort, and the retort closed within the flame chamber and having a hollow hub portion of reduced diameter extending through the end of the furnace and sup- 25 ported for revolution upon the exterior of the furnace, a supply for gas to pass through said hollow hub, a wheel carried exteriorly of the furnace by said hollow hub, and rolls upon which said wheel is sup- 30 ported.
27. The combination with a furnace having a flame chamber, of a retort in said flame chamber, comprising a casting of the herein-described nichrome, said retort ex- 35 tending through the ends of the furnace, means upon the exterior of the furnace for supporting the retort for revolution, said furnace substantially closed at one end and having an opening smaller than the body of 40 the retort, and the retort closed within the flame chamber and having a hollow hub portion of reduced diameter extending through the end of the furnace and supported for revolution upon the exterior of 45 the furnace, a supply for gas to pass through said hollow hub, a wheel carried exteriorly of the furnace by said hollow hub, and rolls upon which said wheel is sup- 50 ported, a driving gear being also carried upon said projecting hollow hub.
28. A revoluble closed carburizing retort in the form of a tubular body of the herein-described nichrome, and having a reduced hollow hub portion at one end to pass 55 through an opening in the furnace of less diameter than the body of the retort, and a cover or lid at the opposite end, and also having a supporting wheel on said hollow hub.
60. 29. A revoluble closed carburizing retort in the form of a tubular body of the herein-described nichrome, and having a reduced hollow hub portion at one end, to pass through an opening in the furnace of less
- diameter than the body of the retort, a 65 cover or lid at the opposite end, and also having a supporting wheel on said hollow hub, and a driving gear on said hollow hub.
30. The combination with a furnace having separate manifolds for supplying fuel thereto, of a retort having a removable cover and mounted in said furnace, a head settable for determining the capacity of the work chamber in said retort, an assortment of stems whereby said head may be connected to said cover at different distances therefrom, and means for cutting out a manifold so as to heat the retort to an extent appropriate to the position of said head. 70
31. The combination with a furnace and burners for supplying fuel thereto, of a retort in said furnace, provision being made for regulating the effective length of said retort, and means for cutting out certain of said burners, so that the furnace may be 75 heated by the remaining burners to an extent appropriate to the effective length of the retort. 80
32. The combination with a furnace having a flame chamber and provided with fuel-supplying means, including a series of manifolds extending along said chamber, of a retort mounted in said chamber, means for varying the effective length of said retort, and means for cutting out one or more 85 manifolds, to enable only the effective length of the retort to be heated by the remaining manifolds. 90
33. The combination with a furnace provided with a succession of fuel-supplying manifolds, of a retort mounted in said furnace, a cover for said retort, a head settable within the retort, an assortment of stems for connecting said cover to said head at varying distances, whereby the effective 95 length of the retort may be varied, and means for cutting out any manifold independently of the others. 100
34. The combination with a furnace and a retort therein, of a series of fuel-supplying manifolds extending along the furnace, and means for cutting out any manifold independently of the others. 110
35. The combination with a retort, of a cover therefor, and a head settable to different positions within the retort to vary the length thereof, provision being made for connecting said head to said cover at substantially different distances therefrom within the portion of the retort which is 115 directly exposed to heat, so that the cover and head may be withdrawn together from the retort, and so that the effective capacity of the retort may be substantially varied. 120
36. The combination with a furnace, of a succession of fuel-supplying manifolds extending along said furnace, the manifolds on one side paired with those on 125

- the opposite side of the furnace, and the manifolds in each pair being in open communication with each other, and means for cutting off any pair of manifolds at will.
- 5 37. The combination with a furnace, of a succession of fuel-supplying manifolds extending along said furnace, the manifolds on one side paired with those on the opposite side of the furnace, and the manifolds in each pair being in open communication with each other, and means for supplying mixed air and fuel to each manifold independently of the others.
- 10 38. The combination with a retort having a flange, of a cover having hooks to catch over the flange at any portion thereof, and individual means for drawing said hooks to hold the cover to the retort.
- 15 39. The combination with a retort having a flange, of a cover having independently movable hooks to catch over said flange at any portion thereof, each hook capable of both a turning movement, and rotatable means for tightening the hooks upon the flange to catch over the flange, and an end-wise sliding movement to tighten the cover to draw the cover against the retort.
- 20 40. The combination with a retort having a flange, of a cover having housings, hooks mounted to slide in said housings, each housing having a pivot pin, and each hook being slotted to engage said pin, and threaded means connected to the housings to draw the hooks against the flange.
- 25 41. The combination with a furnace having a flame chamber and having at one end a large opening and at the other end a small opening, of a retort cast of the herein-described nickel alloy and comprising a barrel portion which projects through said large opening and a hub portion which projects through said small opening, and exterior means upon the ends of the furnace for supporting said retort by means of said projecting portions, the dimensions of said openings approximating those of said casting.
- 30 42. The combination with a furnace having a flame chamber and having at one end a large opening and at the other end a small opening, of a retort cast of the herein-described nickel alloy and comprising a barrel portion which projects through said large opening and a hub portion which projects through said small opening, exterior means upon the ends of the furnace for supporting said retort by means of said projecting portions, the dimensions of said openings approximating those of said casting, said hub portions being hollow, and means being connected to supply metal-treating gas through said hollow hub.
- 35 43. A retort cast of the herein-described nickel alloy, in the form of a cylindrical barrel open at one end and closed at the other end, and a hollow hub portion of reduced diameter projecting from the closed end.
44. As a new article of manufacture, a cylindrical retort in the form of a barrel open at one end and having a head at the other end, and a hollow hub of reduced diameter projecting from said head, said barrel, head and hub cast in one piece of the hereinbefore-described alloy comprising about 60 per cent. of nickel, 20 or 30 per cent. of chrome and 10 or 20 per cent. of iron.
45. The combination with a furnace having a flame chamber and having openings in its ends, of a retort having cylindrical end portions fitted relatively closely in said openings to prevent escape of heat, said openings approximately fitting said retort without substantial allowance for permanent expansion of the retort, said retort formed of nichrome or an alloy of nickel, chrome and iron, nickel forming the main portion of the alloy to prevent the permanent expansion of the barrel to close said openings by reason of successive case-hardening operations in said retort.
46. A retort in the form of a cast cylinder of the herein-described nichrome, said retort comprising extensions whereby the same may be supported at the exterior of the furnace, and closed at its ends between said extensions.
47. A retort in the form of a cast cylinder of the herein-described nichrome, said retort comprising extensions whereby the same may be supported at the exterior of the furnace, and closed at its ends between said extensions, one of said closed ends being cast integral with said retort, and the other closed end being removable.
48. A retort in the form of a casting of nichrome, comprising extensions whereby the same may be supported at the exterior of the furnace, said retort closed at one of its ends and having a hub portion of substantially reduced diameter to form one of said extensions, to permit such extension to pass through a hole in the furnace wall of substantially less diameter than the body of the retort, and a removable closure for the other end of the retort.
49. A retort in the form of a casting of nichrome, comprising extensions whereby the same may be supported at the exterior of the furnace, said retort closed at one of its ends and having a hub portion of substantially reduced diameter to form one of said extensions, to permit such extension to pass through a hole in the furnace wall of substantially less diameter than the body of the retort, and a removable closure for the other end of the retort, said hub portion having an

opening extending from its outer end to the interior of said retort, to serve as a duct for carburizing gas.

50. A revoluble carburizing retort in the 5 form of a tubular body of nichrome having a closed integral end provided with an integral extension in the form of a hub of substantially less diameter than said body, to extend through the wall of the furnace and 10 permit the opening in said wall to be of substantially less diameter than the body of the retort.

51. A revoluble carburizing retort in the 15 form of a tubular body of nichrome having a closed integral end provided with an integral extension in the form of a hub of substantially less diameter than said body, to extend through the wall of the furnace and permit the opening in said wall to be 20 of substantially less diameter than the body of the retort, said hub provided with a supporting wheel and a driving gear, and the opposite end of said retort having an extension to project through the opposite wall 25 of the furnace, and also having a cover removable through said extension.

52. The combination with a furnace having 30 burners which heat iron and steel articles to white heat, said furnace comprising a flame chamber, of a carburizing retort in said flame chamber capable of withstand-

ing the heat thereof and of preserving its dimensions through an indefinite number of carburizing operations, and formed of the herein-described nichrome, said retort having 35 end portions projecting through the walls of the furnace and supported exteriorly of said walls; said walls having openings through which said end portions project, said openings approximating the dimensions of said retort without substantial allowance for permanent expansion of the latter.

53. The combination with a furnace having 40 a flame chamber, of a retort in said flame chamber, comprising a casting of the herein-described nichrome, said retort extending through the ends of the furnace, and means 45 upon the exterior of the furnace for supporting the retort for revolution, said furnace substantially closed at one end and having an opening smaller than the body of the retort, and the retort closed within the flame chamber and having a hub portion of 50 reduced diameter extending through the end 55 of the furnace and supported for revolution upon the exterior of the furnace.
